ASSIGNORS TO FRED BUTTERFIELD & CO. INC., OF NEW YORK, N. Y., A CORPORA-
TION OF NEW YORK.

DESIGN FOR FLOCKED VOILE FABRIC.

Application filed August 18, 1922. Serial No. 3,429. Term of patent 3½ years.

To all whom it may concern:

Be it known that we, EDWARD B. VANDER-
GAW and JULES HEINRICH, citizens of the
United States, residing, respectively, in the
borough of Brooklyn and the borough of
Manhattan, in the city and State of New
York, have jointly invented a new, original,
and ornamental Design for Flocked Voile
Fabric, of which the following is a specifici-

cation, reference being had to the accom-
panying drawing, forming part hereof.

The figure is a plan view of a piece of
fabric showing our new design.

We claim:

The ornamental design for flocked voile
fabric, as shown.

EDWARD B. VANDERGAW.

JULES HEINRICH.
